Attorney

UNITED STATES PATENT OFFICE.

FRANK B. TWINING, OF TROY, NEW YORK, ASSIGNOR TO GEO. P. IDE & COMPANY, INC.,
OF TROY, NEW YORK, A CORPORATION OF NEW YORK.

SOFT TURNOVER COLLAR.

Application filed August 15, 1921. Serial No. 492,499.

To all whom it may concern:

Be it known that I, FRANK B. TWINING, a citizen of the United States, residing at Troy, in the county of Rensselaer and State 5 of New York, have invented certain new and useful Improvements in Soft Turnover Collars, of which the following is a specification.

Many attempts have been made to produce 10 a soft unstarched turn over collar, all with more or less success, by placing various kinds of rigidifying attachments or plies in the collar, but these have been found more or less objectionable, especially those where- 15 in the reinforcing element is detachable, because of the liability of loss of the element, but notwithstanding these objections the soft turn over collar has become a very popular collar and there is a large demand 20 for them.

Attempts have been made to make a collar of a very rigid or stiff material, but in such instance it was found necessary to weaken the fabric along the line of fold, but even 25 this is objectionable because it makes the collar weak at a point where it receives the most wear, consequently the collar will give away first at such weakened line.

The object of my invention is to produce 30 a soft collar, preferably from a multiply interwoven fabric, which will have a natural predetermined folding line or guide for the folding of the collar, without in any degree weakening the fabric of the collar, thereby 35 producing a very desirable soft turn over collar with no weakened zones, no detachable rigidifying elements, and free from the objections of soft collars prior to my invention.

My invention consists of a soft folding 40 collar from one piece of fabric made up of an inner and outer panel with an intermediate strengthened fold portion.

My invention consists further of a collar comprising a neck band and a turn over top 45 portion made from a fabric of a plurality of interwoven plies with additional interwoven ply or plies at the juncture of the neck band and turn over top portion.

My invention consists further of a collar, 50 cuff and the like, made from a multiply interwoven fabric of uniform thickness throughout having an intermediate thickened or stiffened portion formed by one or more added interwoven plies at the fold line 55 of the collar.

While I have, for the purposes of disclosing my invention, shown it embodied in a soft turn down collar, it will be understood that the invention can be practiced in the manufacture of collars designed to be 60 starched and that the invention can be utilized in standing collars that have fold lines at the front.

In the drawings—

Figure 1 is a plan view of a collar, laid 65 flat and embodying my invention.

Figure 2 is a perspective view of the collar folded, one end of the top fold turned back.

Figure 3 is a sectional view on the line 70 3—3, Figure 2.

The reference numeral 1 designates the neck band and 2 the turn over top of the neck band, which may be of any desired pattern; the neck band is provided with the 75 usual button holes 3, 4 and 5.

The collar is made from a multiply interwoven fabric; the several layers or plies being woven from cotton, linen or other thread of any suitable kind and quality appropriate to collar manufacture. The facing 80 of the turn over top portion may be made of thread of different quality or character than the other plies.

The fabric for my improved collars is 85 woven with additional interwoven threads in the weaving of the fabric, which extend longitudinally of the collar at the juncture, or zone of juncture of the neckband and turn over top portion as indicated by the reference 90 numeral 6, which additional interwoven threads increase the thickness of the fabric at the fold zone of the collar and form a natural predetermined line of folding of the collar. These additional threads, constitute 95 an edge fold portion connecting the neck band, and a fold over top and constitute a thickened or stiffened part of the multiply interwoven fabric.

I have found that the fabric from which 100 I make my collar can be woven on existing machines without making any changes in the machines, therefore manufacturing cost is not increased from that standpoint.

Collars have been made for me embodying 105 my invention, which have been found to possess all the advantages of soft unstarched collars, plus the advantages of my invention, among which is the fact that the collar stands up well without starching, is of com- 110

parative stiffness, and is free from buckling or wrinkling, the thickened portion constituting predetermined fold line whereby the collar will always have the proper set on the neck of the wearer without starching.

Another advantage of having this thickened or stiffened fold line guide is that it functions to give the collar a neat set around the neck of the wearer inasmuch as it holds

10 the top edge of the collar in a graceful curve and prevents the top edge from breaking or puckering.

What I claim is:

15 1. A folding collar or cuff woven in one piece made up of a neck band and a turn down portion and a strengthened fold portion adjacent the fold line of the collar.

20 2. A folding or turned down collar made up of a multiply interwoven fabric, forming both the neck band and the turn down portions of the collar, an added interwoven thickness near the top of the neck band portion of the collar to provide an increased thickness and stiffness near the fold line be-

tween the neckband and the folding portion 25 of the collar.

3. A folding collar having a neck band portion and a turn down portion of a thickness to impart stiffness to the collar, one of said portions having an integral thicker 30 zone adjacent its upper edge to which the other portion is secured, the edge of said zone defining the fold line.

4. A folding collar having a neck band portion and a turn down portion of appropriate thickness to impart stiffness to the collar, the neck band having an integral upper edge relatively stiffer than the balance 35 of the neckband the edge of the stiffer edge defining the fold line.

40 5. A folding or turn down collar comprising a neck band portion and a turn down portion, composed of a plurality of interwoven plies, there being additional integral interwoven warp threads near the juncture 45 between the band and turn down portion.

In testimony whereof I affix my signature.

FRANK B. TWINING.
